UNITED STATES PATENT OFFICE

151,116

DESIGN FOR A TABLE ORNAMENT

Charles W. Biener, Yakima, Wash.

Application October 4, 1946, Serial No. 133,769

Term of patent 7 years

(Cl. D29—23)

To all whom it may concern:

Be it known that I, Charles W. Biener, a citizen of the United States of America, residing at Yakima, in the county of Yakima and State of Washington, have invented a new, original, and ornamental Design for a Table Ornament, of which the following is a specification, reference being had to the accompanying drawing, forming a part thereof, wherein:

Figures 3 and 4 are end views.

I claim:

The ornamental design for a table ornament, as shown.

CHARLES W. BIENER.
